UNITED STATES PATENT OFFICE.

HENRY A. BEHN, JR., OF WEEHAWKEN, NEW JERSEY.

SUN-DIAL.

SPECIFICATION forming part of Letters Patent No. 252,418, dated January 17, 1882.

Application filed November 10, 1881. (No model.)

To all whom it may concern:

Be it known that I, H. A. BEHN, Jr., of Weehawken, in the county of Hudson and State of New Jersey, have invented certain new and useful Improvements in Sun-Dials; and I do hereby declare the following to be a full, clear, and exact description of the invention, such as will enable others skilled in the art to which it pertains to make and use it, reference being had to the accompanying drawings, which form part of this specification.

My invention relates to an improvement in sun-dials; and it consists in the combination of a weighted rod or upright for casting the shadow, and a slide which can be pushed inward so as to catch under the weighted end of the rod and hold it in a horizontal position while the dial is being carried around or is closed up, as will be more fully described hereinafter.

The object of my invention is to weight the lower end of the rod or upright for casting the shadow, so that it can be held in a horizontal position while the cover of the dial is closed and while the instrument is being transported, and then when it is desired to use the dial it is only necessary to draw out the slide and the rod or upright will automatically spring into position.

Figure 1 is a plan view of my invention. Fig. 2 is a vertical section of the same, showing the rod in one position in solid lines and in another in dotted lines.

30 A represents a suitable frame, of any desired shape, size, or construction, and which has the dial-plate B marked or formed upon its face in any suitable manner. Through this plate is made a slot, C, which terminates at one end in an enlarged circular opening, while the other 35 end extends through to the edge of the plate itself. In this slot, at the center of the plate, is pivoted the upright or rod D, which is weighted at its lower end, and which extends

upward far enough above its pivot to cast its shadow to the outer edge of the dial-plate. 45 The lower end of this dial is weighted, so that whenever it is free to move the weight will cause the upright to assume a vertical position. In order that this rod may be held in a vertical position, so that the cover of the dial 50 can be closed down to protect the different parts, or while the dial is being transported, the slide E, having its inner end so shaped as to catch under the weight on the lower end of the rod, is used. When this slide is drawn 55 outward, so as to no longer catch under the weighted end of the rod, the rod instantly assumes a vertical position. When the rod is forced down to a horizontal position, so that its 60 weighted end rises through the opening that is made at one end of the slot, and the slide is then forced inward, the inner end of the slide forms a support for the weight, and the rod is then held firmly in position.

Also attached to the dial-face is an ordinary 65 compass, G, which serves to indicate the position in which the dial is to be placed or held so as to give the correct time.

Having thus described my invention, I claim—

1. In a sun-dial, the weighted pointer or rod, in combination with a slide which supports the rod in a horizontal position, substantially as shown.

2. In a sun-dial, the combination of a pivoted weighted rod or pointer, a slide for supporting the pointer in a horizontal position, a slotted dial-plate, and the compass, the parts being arranged to operate substantially as described.

In testimony whereof I affix my signature in presence of two witnesses.

HENRY AUGUST BEHN, JR.

Witnesses:

WILLIAM MEIXNER,
FREDERICK C. WIENKEN.
